SILO-DOOR.

1,331,770.

Specification of Letters Patent. Patented Feb. 24, 1920.

Application filed January 5, 1918. Serial No. 210,790.

To all whom it may concern:

Be it known that we, HARRIS HULEN and CHARLES F. BROWN, citizens of the United States, residing at Kansas City, in the county of Jackson and State of Missouri, have invented certain new and useful Improvements in Silo-Doors, of which the following is a specification.

This invention relates to silo doors and more especially to hinge and fastening means therefor, and the object of the invention is to produce efficient and at the same time simple, strong, durable and economical devices of the character set forth.

To this end the invention consists in certain novel and useful features of construction and combinations of parts as hereinafter described and claimed; and in order that it may be fully understood reference is to be had to the accompanying drawing, in which—

Figure 1, is an outer face view of a segment of a silo equipped with a door embodying the invention.

Fig. 2 is an enlarged horizontal section on the line II—II of Fig. 1.

Fig. 3, is a detail perspective view of a clamping lever for the door.

Referring to the drawing in detail, 1—1 indicates the two side bars of a segment of the silo, and 2 are horizontal bars connecting bars 1 at regular intervals from the bottom to the top of the silo, it being understood that the latter is composed of a series of said segments arranged in a circle, all of the segments being completely boarded up with staves except the one adapted for the reception of the doors, which one has a vertical partition 2^a forming one side of the series of superposed door openings 2^b. The particular construction of the silo is of no importance in this connection however as it is covered by patent, and also because this invention is applicable to any silo provided with a series of superposed openings of suitable size and form for the reception of the doors.

The doors for the openings may be of any suitable construction, but preferably consist of rectangular frames for fitting within the openings, and flooring boards secured vertically to such frames and projecting marginally beyond the same sufficiently to completely cover the openings and bear against the inner sides of the vertical bars

1—2^a and horizontal bars 2. One of the doors is shown, 3 and 4 indicating the horizontal and vertical bars respectively of the frame, and 5 the vertically arranged flooring boards secured to the inner side of the frame and tongue and grooved together at their abutting edges.

The hinge for supporting each door, consists of a vertical part 6 of length to fit within the door opening, a pair of outwardly bowed arms 9 projecting in the same direction from opposite ends of the part 6, and a pair of vertically-alined pivots 10, projecting toward each other and pivotally through the said frame of the door, one of the arms 70 9 overlying the topmost bar 3 and the other underlying the bottom bar 3, it being noted by reference to Fig. 2, that the lower arm 9 rests on the underlying cross bar 2 at all times and hence prevents sagging of the door 75 when open. It will also be noted that because the arms 9 are bowed outwardly, it is possible to swing the door completely to one side of the opening and back against the inner side of the silo.

The part 6 of the hinge is the pivot for door movement and is journaled in hinge straps 11 secured within the door opening to one of the side bars 1, each strap being secured at one end by screws or bolts 12 and at 85 the other end by embedment in the said side bar, as at 13.

To secure the door firmly in place and clamp it against the inner side of the silo, a plate 14 is secured to the outer side of one 90 of the vertical bars 4 of the frame, for engagement with a lug 15 secured to the inner side of the bar 1, at the free edge of the door, and an angle lever 16 is pivoted to the vertical bar 4 at the hinge edge of the door 95 for engagement with the part 8 of the hinge frame, the lever having a beveled or cam surface 17 to facilitate engagement with said part and the application of increasing force thereon to draw the door outward until the 100 flooring boards thereof are clamped firmly against the bars 1 and 2, around the opening and exclude air and water from the silo.

To open a door the lever is swung as indicated by the arrow and then pressure is applied to force the hinge edge of the door inward, this movement causing the door to move to the right and effecting disengagement between the plate 14 and the lug 15, after which the door is free to swing to fully 110

opened position. In closing the door the operation described is reversed.

From the above description it will be apparent that we have produced door securing devices embodying the features of advantage mentioned as desirable in the statement of the object of the invention, and which is obviously susceptible of modification in minor particulars without departing from the spirit and scope of the appended claims.

We claim:

1. A silo provided with a door opening, a door for closing the opening, provided with in said opening with a horizontal bar at its outer side and near its lower edge, means for hingedly supporting the door from one side of the door opening, said means closely overlying and being adapted to be supported by the sill of the door opening in the event the door sags regardless of whether it is in operative or inoperative position, and underlying said bar as a support to prevent sagging of the door.
2. A silo provided with a door opening, a door for closing the opening, provided with a pair of horizontal bars at its outer side, and a horizontally-arranged U-frame hinged to the silo at one side of the door opening, with its arms respectively pivoted at their outer ends to said bars, one of said arms closely overlying the uppermost bar and the

other underlying the other bar and closely overlying the sill of the door opening to afford a support against sagging movement of the door.

3. The combination with a silo having a door-opening, a door within the silo to cover said opening, a swing frame hinged to the silo within said opening and at one side thereof and provided with a pair of outwardly-bowed arms pivoted at their free ends to the door and respectively overlying and underlying parts of the door, one of said arms closely overlying the silo at the bottom of said opening to prevent sagging of the door, and means to secure the door firmly clamped over said opening within the silo.

4. A silo provided with a door opening, a door for said opening, provided with a horizontal cleat at its outer side and near its lower edge, means for hingedly supporting the door from one side of the door opening and within said opening, and embodying an outwardly-bowed arm closely overlying and adapted to be prevented from sagging by the sill of the door opening, and underlying said cleat to guard against sagging of the door.

In witness whereof, we have affixed our signatures hereto.

HARRIS HULEN.

CHARLES F. BROWN.
